UNITED STATES PATENT OFFICE.

JOSEPH T. AUGER, OF MINNEAPOLIS, MINNESOTA, ASSIGNOR OF THREE-EIGHTHS TO
E. M. FERGUSON, OF ST. PAUL, MINNESOTA, AND THREE-EIGHTHS TO E. DULAC,
OF MINNEAPOLIS, MINNESOTA.

ROTARY PUMP.

1,348,772.

Specification of Letters Patent. Patented Aug. 3, 1920.

Application filed February 7, 1919. Serial No. 275,543.

To all whom it may concern:

Be it known that I, JOSEPH T. AUGER, a citizen of the United States, residing at Minneapolis, in the county of Hennepin and 5 State of Minnesota, have invented certain new and useful Improvements in Rotary Pumps, of which the following is a specification.

My invention relates to rotary pumps and 10 in particular to pumps of this type for use in connection with fire apparatus. An object is to provide a pump which will have a high degree of efficiency and at the same time will occupy only a comparatively small 15 space.

The full objects and advantages of my invention will appear in connection with the detailed description thereof and the novel features embodied in my inventive idea will 20 be particularly pointed out in the claims.

Referring to the drawings,—

Figure 1 is a vertical section on the line 1—1 of Fig. 2. Fig. 2 is a horizontal section on the line 2—2 of Fig. 1. Fig. 3 is a 25 horizontal section on the line 3—3 of Fig. 1. Fig. 4 is a cross-section on the line 4—4 of Fig. 3. Fig. 5 is a detail view of the rotary pistons. Fig. 6 is a view similar to Fig. 4 showing a slight modification.

30 The casing of the pump consists of three castings as follows: A base casting 10, an intermediate casting 12 and a casting 14. The castings 10 and 12 are secured together so as to form water-tight joints by bolts 16 35 which are located in holes in flanges 18 on the casting 12, and in holes in the top of the casting 10. The castings 12 and 14 are secured together so as to form water-tight joints by bolts 20 which are located in holes 40 in flanges 22 on the casting 12, and in holes in the bottom of the casting 14. On account of this construction the castings may be readily separated from each other to afford 45 easy access to the interior parts. The ends of the base casting have tubular portions which constitute inlet openings 24 leading into an inlet chamber 26. The wall of one side of this chamber is provided with a detachable closure 28 in order that accumulations of refuse material may be removed whenever desired. The bottom wall of the 50 chamber is provided with a screw plug 30 which may be removed for draining the apparatus. The intermediate casting is so

shaped as to have two partially-overlapping 55 cylindrical piston chambers 32, as best shown in Fig. 1. The lower side portions of the intermediate casting are bulged outwardly so as to come on top of the side walls of the lower casting and form lateral 60 admission ports 34 as shown in Fig. 4. As will be seen in Fig. 1, the piston chambers extend downwardly into the inlet chamber and the walls of the piston chambers at their lower line of intersection are provided 65 with a ridge 36 which serves to divide the water which enters the two piston chambers. A piston shaft 38 extends axially through each of the chambers 32 and these shafts may be driven in unison in the usual manner. The two shafts extend through stuffing boxes at both sides of the piston chamber, and outside of the stuffing boxes the shafts are provided with ball bearings 40. The stuffing boxes comprise an annular wall 42 70 within which are the following elements, which surround the shaft. A felt washer or other packing 44 is placed adjacent the wall of the piston chamber, and upon this packing is a metal washer 46. At the other 75 end of the stuffing box is an annular nut 48 and a metal washer 50 which rests upon a felt washer or other packing 52, and the latter in turn rests upon a metal washer 54. The metal washers 46 and 54 are forced 80 apart by a coiled spring 56 whereby the felt washers or packing 44 and 52 are compressed to make a water-tight joint. This construction provides a desirable packing 85 for rotary pumps of this character where it is particularly desirable to provide water-tight joints for the shafts of the rotary pistons. By this construction also water is prevented from reaching the ball bearings 40. The rotary pistons now to be described 90 are preferably provided with annular ribs 39 which engage the packing washers 44 in such manner as to increase the tightness of 95 the joint.

Within the piston chambers the shafts 38 100 are provided with rotary pistons having a plurality of intermeshing piston blades 58. For convenience, and in order to better show the construction of the bridge, only one of the pistons is shown in Fig. 1. Fig. 5 shows 105 in detail the particular construction and operation of the rotary pistons. Referring particularly to this figure each piston mem-

ber consists of four piston blades 58 separated by cavities 60, the bottoms 62 of which are curved upon a large curvature and the side walls 64 of which are straight. Each 5 of the side walls merges by reverse curves into the convex surfaces 66 of the side of the piston blade. The reverse curves form lugs 68 and shallow depressions at 70 from which the water may readily escape when the piston 10 blades are in discharging position on account of the absence of steep engaging surfaces. The outer edges of the piston blades are provided with packing strips 72, and in operation the packing strips on each 15 piston will in alternation come into engagement with the curved bottom 62 of a cavity of the opposing piston member. It will be noticed that on account of the large curvature of the bottom 62 and the straight side 20 walls 64 a slight amount of water is left on each side of the packing 72 in the corners of the cavity. The result of this is that a tight joint is made by the packing strips without possibility of water-lock occurring. 25 The intermediate casting is provided with bridge members 74 having a construction best shown in Fig. 1. A horizontal groove 76 in the bridge extends from one piston shaft to the other, while from the middle 30 of this groove a vertical groove 78 extends to the bottom of the bridge so as to lead back to the lower side of the piston chambers. The intermediate portion of each bridge has an upward extension 80 which is 35 connected to the wall of the intermediate casting by a narrow rib whereby pockets 84, best shown by dotted lines in Fig. 4, are formed at the bottom of the lateral discharge openings where they lead from the piston 40 chambers. On account of this construction a ready escape for grit and gravel from the piston chambers is provided. The intermediate casting, as will appear from Fig. 4, is bulged outwardly at both sides to 45 form the lateral discharge openings 86. Instead of providing the top casting with the customary discharge chamber to which the discharge openings lead, I have provided the following construction. The top casting 50 embodies two curved tubular members 88 extending in opposite directions as best shown in Fig. 3. The members 88 constitute discharge pipes leading directly from the discharge openings, and these pipes have the 55 form of a slight reverse curve which carries them from the lateral discharge openings into longitudinal alignment along a median line of the apparatus and their outer ends may be connected with the hose which carries the water delivered by the pump. In 60 this manner a free and unobstructed passage of water is provided for directly from the pump to the hose. The upper curved surfaces of both piston chambers are extended 65 at 90 beyond the place where the lateral dis-

charge openings 86 begin. This adds to the force with which the piston blades deliver the water out laterally through the openings 86. The walls 90 are not extended sufficiently to meet each other but a gap is left 70 whereby an opening 92 is provided leading into a space in the top casting between the place where the tubular members or discharge pipes 88 lead from the discharge openings 86. Sufficient water to fill this 75 space will be forced up through the opening 92, and this water can escape at both sides into the discharge pipes 88. Above the opening 92 the top casting is provided with an air chamber 94 having an opening 96 in 80 its bottom. Above the air chamber is a priming opening adapted to be closed by a screw plug 98. Fig. 6 shows a slight modification in which discharge pipes 100 lead directly in a vertical direction from the 85 lateral discharge openings 86, which are above the bridge walls 74. A receptacle 102 constitutes an air chamber and is secured to the top of the casing by a screw-threaded coupling 104. 90

The operation and advantages of my invention will be readily understood from the foregoing description. On account of the discharge pipes leading directly from the lateral discharge openings, the efficiency of the 95 pump is increased, since the free discharge of water is not interfered with, while by extending the top surface of the piston chambers beyond the place at which the piston blades begin to force water from the discharge openings, a greater impulse is imparted to the water which is being discharged. The provision of the pockets 84 on each side of the narrow rib 82 gives ample opportunity for sand and gravel to be 100 freely carried out of the piston chambers. The special form of packing for the shafts of the rotary pistons prevents leakage of water at this place. The particular construction of the piston blades causes the water to be forced out through the lateral discharge openings with a free and easy movement, while the manner in which the packing on the piston blades engages the curved surface of the cavity of the coöperating piston 110 member prevents leakage at this place. The bridge members 74 may, if desired, be provided with grooves 85 extending in an inclined direction downwardly and outwardly from the lower sides of the shafts 38 to the lower sides of the ends of the bridge members. This provides for the escape of sand and grit, while a water packing is formed by the pistons operating in connection with the grooves. 115

I claim:

1. A rotary pump comprising a casing containing two overlapping piston chambers provided with lateral intake and discharge openings, bridges separating said intake and 130

discharge openings, rotary pistons having intermeshing blades in said piston chambers, discharge pipes leading directly from said lateral discharge openings, said piston chambers at their top line of intersection being provided with an opening, and an air chamber in said casing above the last-mentioned opening.

2. A rotary pump comprising a casing 10 containing two overlapping piston chambers provided with lateral intake and discharge openings, bridges separating said intake and discharge openings, rotary pistons having intermeshing blades in said piston chambers, 15 each of said bridges being provided intermediate its length with an upward extension, and a narrow rib connecting the vertical central portion of said extension with the outer wall of said discharge openings where- 20 by pockets are formed at the bottom of said discharge openings.

3. A rotary pump comprising a casing 25 containing two overlapping piston chambers provided with lateral intake and discharge openings, bridges separating said intake and discharge openings, rotary pistons having intermeshing blades in said piston chambers, and shafts for said rotary pistons extending through said piston chambers, said 30 bridges being provided with grooves extending in an inclined direction downwardly and outwardly from the lower sides of said shafts to the lower sides of the ends of said bridges.

35 4. A rotary pump comprising a base member having an intake opening and a base chamber, a casing containing a pump chamber having curved walls joined together at the bottom and extending below the top of 40 said base chamber, the said pump chamber

being downwardly curved to conform to said walls, and lateral intake openings leading to the pump chamber from said base chamber and extending to the bottom of said pump chamber, the latter being provided 45 with a lateral outlet opening.

5. A rotary pump comprising a casing containing a pump chamber having side walls connected by curved walls which are joined together at the bottom, a base member 50 having an inlet opening and a base chamber, the latter surrounding the lower part of said pump chamber, lateral intake openings leading to said pump chamber from the opposite sides of said base chamber, the 55 said inlet openings being formed in said side walls and extending to the bottom of said pump chamber, the latter being provided with an outlet opening, and an air chamber above said outlet opening.

6. A rotary pump comprising a base member having horizontal inlet openings and a base chamber, said member having an opening in the top thereof, a casing containing a pump chamber having curved walls closing 65 said opening at the top of said base chamber, the lower portion of said curved walls extending through said opening so as to be submerged in the liquid in said base chamber and said base chamber surrounding the 70 submerged portion of said pump chamber, lateral intake openings leading from said base chamber to said pump chamber and extending to the bottom of said pump chamber, the latter being provided with outlet 75 openings.

In testimony whereof I hereunto affix my signature.

JOSEPH T. AUGER.
